UNITED STATES PATENT OFFICE.

ORRA L. GILLILAND, OF DOYON, NORTH DAKOTA.

SHOCK-LOADER.

1,073,849.

Specification of Letters Patent. Patented Sept. 23, 1913.

Application filed October 18, 1912. Serial No. 726,460.

To all whom it may concern:

Be it known that I, ORRA L. GILLILAND, a citizen of the United States, residing at Doyon, in the county of Ramsey and State 5 of North Dakota, have invented certain new and useful Improvements in Shock-Loaders; and I do hereby declare the following to be a full, clear, and exact description of the invention, such as will enable others 10 skilled in the art to which it appertains to make and use the same.

My present invention has for its object to provide an improved shock loader and is in the nature of or improvement on the 15 shock loader disclosed and claimed in my pending application S. N. 637,327, filed of date, July 7th, 1911.

Generally stated, the invention consists of the novel devices and combinations of 20 devices hereinafter described and defined in the claims.

In the accompanying drawings which illustrate the invention, like characters indicate like parts throughout the several views.

25 Referring to the drawings, Figure 1 is a plan view showing the improved machine with some parts removed; Fig. 2 is a plan view of the machine with the conveyers removed; Fig. 3 is a right side elevation of the 30 machine; Fig. 4 is a rear elevation of the machine; Fig. 5 is a transverse vertical section taken on the line x^5-x^5 on Fig. 1 with some parts removed; Fig. 6 is a view in elevation, some parts broken away and some 35 parts sectioned, showing one of the conveyers looking at the same in the direction of the arrow marked "y" on Fig. 5; Fig. 7 is a detail view in side elevation, some 40 parts being sectioned and some parts being broken away, showing certain of the driving connections shown also, but not as clearly as in Fig. 3; Fig. 8 is a detail in rear elevation showing the driving connections and one of the conveyers; and Fig. 9 is a fragmentary view in rear elevation showing the 45 driving connections and one of the conveyers.

The carrying truck of the machine comprises a truck frame 1, rotary rear axle 2, 50 rear traction wheels 3 secured on the ends of said axle 2, and front wheels 4 journaled on oscillatory knuckles 5 that are pivoted to suitable bearing brackets 6 rigidly secured to the side bars of the said frame 1. The 55 steering of the machine is accomplished by movements of the front wheels 4 and

knuckles 5, and to this end the said knuckles 5 are provided with projecting arms 7 connected by links 8 to the ends of a long steering beam 9 that is intermediately pivoted 60 to a bearing 10 on one of the transverse bars 1^a of the frame 1. The ends of the beam 9 are connected to the opposite ends of a steering cable 11, the intermediate portion of which is wound upon a drum 12 secured to the rod 13 of a steering wheel 14. This rod 13, at its lower end, is journaled in a suitable bearing on an operating platform 1^b carried by the rear portion of the truck frame 1.

The forwardly projecting side bars of the frame 1 are spaced apart to afford a working space for a so-called gathering deck which is preferably in the form of a forwardly inclined gathering fork 15. The 75 gathering fork 15 is adjustably supported from the truck frame 1 by two crank shafts 16 and 17, which, at their ends are journaled in the side of the frame 1, (see Figs. 3 and 4). At the right hand side of the 80 machine, the crank shafts 16 and 17 are provided, respectively, with upwardly projecting arms 16^a and 17^a that are connected to the front ends of operating rods 18 and 19. The rear ends of the said rods 18 and 85 19 are connected to latch levers 20 and 21 that are pivoted to and coöperating with lock segments 22 secured, as shown, on the operating platform 1^b (see particularly 90 Figs. 3 and 4). By manipulation of the crank shafts 16 and 17 the gathering fork 15 may be adjusted both vertically and longitudinally of the machine.

Extending rearward and upward from the gathering fork 15 is a so-called primary 95 elevator deck 23, which, as shown, is made up of forwardly inclined longitudinal slats, and transverse connecting bars. The slats of the said deck 23, at their front ends are connected by hinges 24 to the slats of the 100 gathering fork 15, at points considerably rearward at the front ends of the latter (see particularly Figs. 2 and 3). The rear portion of the so-called primary elevator deck 23 is supported from the frame 1, by a transverse crank shaft 25, (see Figs. 3 and 4), which crank shaft permits forward and rearward adjustments of the primary elevator deck. This co-called primary elevator deck is, in a sense, a supplemental frame which 110 includes a deck and is arranged to support endless conveyers, presently to be described.

Carried by and rigidly secured to the rear end portion of a so-called primary elevator deck 23, is a so-called secondary elevator deck 26. This deck 26 extends transversely 5 of the machine and projects at the right hand side thereof. The entire portion thereof inclines forwardly at an angle of about 45 degrees, and the projecting right hand portion thereof rises obliquely at an angle 10 of about 30 degrees to the horizontal. Rigidly secured on the sides of the primary elevator deck 23 is a pair of conveyer frames 27 and 28, which, in the direction transversely of the machine, are tipped or canted 15 over toward each other at an angle of about 30 degrees to the perpendicular. The left hand frame 27 terminates at the front edge of the secondary elevator deck 26, but the right hand frame 28 extends along the front 20 edge of the inclined right hand portion of said deck 26, and its rear face stands at an angle of about 90 degrees to the projecting portion of the said deck 26. Journaled in the left hand frame 27 near the ends thereof, and in the ends and angular corner of the right hand frame 28, are oblique shafts 29 provided with upper and lower sprocket wheels 30, over which upper and lower sprocket chains 31 are arranged to run. Fas- 30 tened to and surrounding each pair of upper and lower sprocket chains 31 are slatted conveyer belts 32 that are provided with obliquely projecting wide conveyer blades 33. Certain of the slats of the belt 32 are pro- 35 vided with depending trunnions 34, on which are journaled small wheels 35 arranged to run in endless channel-shaped guides 36. These channel shaped guides 36 are rigidly secured to the lower portions of 40 the frames 27 and 28 and follow the lines of movement of the lower portions of the conveyer belts 32.

The purpose of cutting the lower edges of 45 the conveying blades 33 obliquely is to cause the same to clear the bars of the primary elevator deck 23, as shown in Fig. 5, and to clear the inclined secondary elevator deck 26, as shown in Fig. 1. To brace said blades 33 from the said belts 32 without interfer- 50 ing with the movements of the belt around the sprocket wheels 31, oblique brace rods 37 are hinged to the said blades and to adjacent slats of the said belts, as shown in Fig. 6.

To hold the right hand sprocket chains 31 and right hand belt 32 in operative position at point opposite to the place where they pass around the intermediate sprockets 30, idle guide wheels 38 are journaled on trun- 60 nions 39 secured on the frame 28, as best shown in Figs. 1 and 3. These wheels 38 are so spaced that the blades 33 pass freely between them.

Mounted on the lower or left hand rear 65 portion of the secondary elevator deck 26 is

an auxiliary conveyer comprising a frame 40, and an endless belt 41 having conveyer blades 42. The said conveyer belt 41 runs over suitable guide rollers, the shafts 43 of which are journaled in the frame 40, and one 70 of which projects at its lower end and is provided with a beveled gear 44, shown in Figs. 4 and 7.

The driving connections to the several conveyers, as shown, are as follows: Directing attention first to Fig. 4, it will be noted that the rear axle 2, which is driven from the rear traction wheels 3 is provided with a centrally located sprocket 45. A sprocket chain 46 runs over the sprocket 45 and over the sprocket 47 on a transverse shaft 48 journaled in suitable bearings on the primary deck 23 (see Figs. 3, 4, 7 and 8). At its projecting right hand end, the shaft 48 (see particularly Fig. 8) is provided with a beveled gear 49 that meshes with a bevel gear 50 on the lower end of a shaft 51 that is journaled in suitable bearings on the bottom of the oblique laterally projecting portion of the right hand frame 29. At its upper end, this shaft 51 is provided with a bevel gear 52 that meshes with a bevel gear 53 on the depending end of the upper or outermost conveyer driving shaft 29. By this means, the right hand conveyer belt 32 is driven. The rear shaft 29 of the left hand conveyer (see Fig. 9) is provided at its projecting lower end with a beveled gear 54 that meshes with a beveled gear 55 on the transverse shaft 48. The upper shaft 43 of the auxiliary conveyer (see Figs. 4 and 7) has, as already stated, at its depending lower end a beveled gear 44. This beveled gear 44 meshes with a beveled gear 56 on the upper end of an oblique shaft 57 mounted in suitable bearings on the deck 23 and provided at its lower end with a beveled gear 58 that meshes with a beveled gear 59 on the said transverse shaft 48.

Under advance movement of the machine, the shocks, bundles or loose grain along the line of travel, will be picked up by the fork and delivered onto the lower front end of the primary elevator deck 23, and there they will be taken up by the blades 33 of the two conveyer belts 32 and will be carried upward and delivered to the lower inclined portion of the secondary elevator belt 26. At this point the blades 42 of the auxiliary conveyer belt 41 act upon the bundles to carry the same out of engagement with the blades of the left hand conveyer and to deliver the same solely to the blades of the right hand conveyer, by which latter, the upward movement of the bundles on the inclined laterally projecting portion of the said secondary elevator deck 26, will be continued. By the said deck 26 and the blades of the said right hand conveyer, the bundles will be elevated to a point of dis- 120 125 130

charge where they will be adapted to be delivered into the box of the wagon driven by the side of the machine. The inclination of the frames 27 and 28 and of the conveyer belts 32, transversely of the machine and over the primary elevator deck 23 causes the bundles to be held in compact form, as in shock, while they are being elevated to the secondary elevator deck 26. The inclination 5 of the said secondary elevator deck longitudinally of the machine and the inclination of the transversely extended portions of the frame 28 and of the right hand conveyer belt 32 causes these bundles to be tilted or 10 canted over against the said belt 32 so that the discharge movement thereof will be accomplished by the single conveyer, to-wit, by the transversely moving portion of the 15 said right hand conveyer belt 32.

20 It will be noted that the front end portion of the primary elevator deck 23 is supported directly by the gathering fork 15, and that the said gathering fork is adjustably supported from the truck frame 1 by 25 the crank shafts 16 and 17. Adjustments of the crank shaft 16 serve to move the fork 15 forwardly and rearwardly, and adjustments of the crank shaft 17 serve to raise and lower the front end of the said fork. 30 The rear portion of the deck 23 being supported by the oscillatory crank shaft 25, is free to partake of the adjustments of the fork 15 to which the front end thereof is connected by hinges 24.

35 Figs. 1 and 4 are complete views except for parts broken away in Fig. 3, for the sake of clearness and to avoid complications, the conveyer belts 32 are removed from the sprocket chains 31.

40 What I claim is:

1. In a machine of the kind described, the combination with a truck, of a gathering deck supported from the frame of said truck, an inclined elevator deck receiving 45 from said gathering deck and adjustably supported in part by said receiving deck and in part by said truck frame, and a pair of opposite endless conveyers operative to carry the bundles upward on said elevator 50 deck and converging toward their upper portions so that they overlie said elevator deck.

55 2. In a machine of the kind described, the combination with a truck, of a gathering fork at the front thereof, an inclined elevator deck receiving from said fork, and a pair of opposite endless conveyer belts provided with projecting blades and converging toward their upper portion so that they 60 overlie said elevator deck.

65 3. In a machine of the kind described, the combination with a truck, of a gathering fork at the front of said truck, an inclined primary elevator deck receiving from said fork, a secondary elevator deck receiving

from said primary deck and set in a plane that inclines obliquely toward the front of the machine, and conveyers coöperating with said deck to move the bundles from the receiving portion of said primary deck 70 to the delivery portion of said secondary deck.

4. In a machine of the kind described, the combination with a truck, of a gathering fork at the front thereof, an inclined primary elevator deck receiving from said fork, a transversely inclined secondary elevator deck receiving from said primary deck, and a pair of opposite endless conveyers coöperating to carry the bundles over said primary deck, and one thereof extending along 80 said secondary deck and serving to carry the bundles over the latter.

5. In a machine of the kind described, the combination with a truck, of a gathering fork at the front thereof, an inclined primary elevator deck receiving material from said fork, a transversely inclined secondary elevator deck receiving from said primary deck, and a pair of opposite endless conveyers coöperating to carry the bundles over 85 said primary deck, one thereof extending along said secondary deck and serving to carry the bundles over the latter, and an auxiliary conveyer on the receiving portion 90 of said secondary deck serving to assist in starting the bundles upward on said secondary deck.

6. In a machine of the kind described, the combination with a truck, of a gathering 100 fork at the front thereof, an inclined primary elevator deck receiving from said fork a transversely inclined secondary elevator deck receiving from said primary deck, a pair of opposite endless conveyers coöperating to carry the bundles over said primary deck, one thereof extending along said secondary deck and serving to carry the bundles over the latter, and an endless blade-equipped auxiliary conveyer on the receiving 105 portion of said secondary deck, substantially as described.

7. In a machine of the kind described, the combination with a truck, of a gathering fork at the front thereof, an inclined elevator deck receiving from said fork, a secondary elevator deck receiving from said primary deck and projecting at one side of the machine, the said secondary deck being set in a plane that inclines obliquely toward 115 the front and to one side of the machine, and a pair of opposite endless conveyers coöperating to carry the bundles over said primary deck, and one thereof extending also along the lower front side of the transversely projecting portion of said secondary deck and serving to carry the bundles over the same.

8. In a machine of the kind described, the combination with a truck, of a gathering 120

fork at the front thereof, an inclined elevator deck receiving from said fork, a secondary elevator deck receiving from said primary deck and projecting at one side of the machine, the said secondary deck being inclined both in a direction longitudinally and transversely of the machine, and a pair of opposite endless conveyers coöperating to carry the bundles over said primary deck, 10 one thereof extending also along the lower front side of the transversely projecting portion of said secondary deck and serving to carry the bundles over the same, the opposing portions of said endless conveyers being inclined toward each other so that they overlie said primary deck, and the transversely extended portion of the one conveyer being forwardly inclined.

9. In a machine of the kind described, the combination with a truck, of a gathering fork at the front thereof, an inclined elevator deck receiving from said fork, a secondary elevator deck receiving from said primary deck and projecting at one side of the machine, the said secondary deck being inclined both in a direction longitudinally and transversely of the machine, and a pair of opposite endless conveyers coöperating to carry the bundles over said primary deck, 25 and one thereof extending also along the lower front side of the transversely projecting portion of said secondary deck and serving to carry the bundles over the same, and an endless auxiliary conveyer overlying the rear edge of the receiving portion of said secondary deck.

10. In a machine of the kind described, the combination with a truck, of a gathering fork at the front thereof, an inclined elevator deck receiving from said fork, a secondary elevator deck receiving from said primary deck and projecting at one side of the machine, the said secondary deck being

inclined both in a direction longitudinally and transversely of the machine, and a pair 45 of opposite endless conveyers coöperating to carry the bundles over said primary deck, one thereof extending also along the lower front side of the transversely projecting portion of said secondary deck and serving to carry 50 the bundles over the same, the opposing portions of said endless conveyers being inclined toward each other so that they overlie said primary deck, the transversely extended portions of the one conveyer being forwardly inclined, and a transversely extended forward inclined endless auxiliary conveyer overlying the rear edge of the receiving portion of said secondary deck, substantially as described.

11. In a machine of the kind described, the combination with a truck, of a gathering fork, a pair of crank shafts adjustably supporting said fork from the truck frame, means for operating said crank shafts, an 65 elevator deck overlying and receiving from said fork, and means for carrying the bundles upward over said elevator deck.

12. In a machine of the kind described, the combination with a truck, of a gathering fork, a pair of crank shafts adjustably supporting said fork from the truck frame, means for operating said crank shafts, an elevator deck overlying and receiving from 70 said fork, and means for carrying the bundles upward over said elevator deck, a transversely extended inclined secondary elevator deck receiving from the first named deck, and means for carrying the bundles over 75 said secondary deck.

In testimony whereof I affix my signature in presence of two witnesses.

ORRA L. GILLILAND.
